UNITED STATES PATENT OFFICE.

JULIUS EMMUEL CARLSON, OF EDGEWATER, NEW JERSEY.

DRILL PRESS.

Application filed May 8, 1921. Serial No. 466,418.

To all whom it may concern:

Be it known that I, JULIUS E. CARLSON, a citizen of the United States, and resident of Edgewater, in the county of Bergen and 5 State of New Jersey, have invented a new and Improved Drill Press, of which the following is a full, clear, and exact description.

My invention relates to a drill press or 10 machine of a similar character, and aims to provide certain new and useful improvements in connection with this class of device.

It is well understood that considerable 15 difficulty has been experienced in connection with drill presses and similar machines in that the same are limited according to their size, to relatively small classes of work, thus a medium size machine of the character 20 stated is capable of being used in connection with only such articles as are capable of being accommodated upon its table, or within the distance existent between its supporting column and working 25 head.

Thus the customary machine shop, where but one type of each machine is available, is incapable of handling wide ranges of work in that the machines are unable to accommodate the same.

With this in mind my present invention aims to provide a drill press or machine of similar character which shall be constructed in its main elements in the usual 35 manner, but which shall embody certain requirements of construction rendering the machine capable of accommodating any size of work.

Another object of this invention is the 40 construction of a device of the nature specified which shall be enabled to accomplish the purpose brought out in the preceding paragraph by means of relatively simple provisions.

With these and further objects in view, 45 reference is had to the attached sheet of drawings which illustrate one practical embodiment of my invention, and in which;

Figure 1 is a side view of a machine embodying my improved construction and showing the conventional elements somewhat diagrammatically.

Figure 2 is a plan view of the machine.

Figure 3 is a sectional side view taken 50 along the line 3—3 and in the direction of the arrows indicated in Figure 1, and

Figures 4 and 5 are sectional views taken respectively along the lines 4—4 and 5—5 of Figure 2 in the direction of the arrows indicated in these figures.

Referring now more particularly to Figure 1 it will be seen that the reference numeral 10 indicates the conventional supporting column arranged upon a base 11 suitably secured to a supporting surface. 60 Also a table 12 is associated with the supporting column 10 and is adapted to support a piece of work which is to under lie the head 13 of the press, the latter being in turn carried by means of the platform 70 14 secured to the upper end of the supporting column.

All of the foregoing is conventional construction and it will be seen that usually the difficulty which has been experienced 75 is to be predicated to the limited space afforded between the supporting column 10 and head 13, as well as the distance of the latter upon the supporting surface and the intervening table 12.

With this in view, reference being had to Figure 3, as well as Figure 1, it will be seen that the table 12 is mounted upon an arm 15 which latter is attached to a collar 16 slidably encircling the column 10. 80 A ring 17 which is preferably contractible, as has been indicated at 18 encircles the collar 16 and is formed with an extended portion 19 provided with an interiorly 85 screw threaded opening capable of being 90 engaged by the screw threads of a shaft 20 rotatably mounted adjacent the supporting column 10.

Thus it will be understood primarily that the distance between the table and 95 working head may be varied by rotating the gear 21 which, meshing with the gear 22 secured to the shaft 20 effects a rotation of the latter. This will in turn cause the extended portion 19 of the ring 17 to act as 100 a traveler in that the same will travel longitudinally of the shaft 20, and by virtue of the fact that it is secured to the collar 16, will cause the latter also to move in a vertical plane, thus varying the distance between the upper surface of the table 12, 105 and the head 13, permitting of articles of various sizes to be accommodated irrespective of any certain limits of their height.

If it is thought that the table 12 is incapable of being manipulated to such an extent as to permit of the work being accommo-

dated, this objection may readily be overcome by loosening the element 18, and upon this occurring it will be obvious that the collar 16 may be rotated with freedom with respect to the ring 17, thus allowing the table 12 to be swung out of the path of the head 13, and obviously permitting of work being disposed under the head 13 and being operated upon thereby.

10 Thus all but the largest sizes of work are capable of being operated upon and with a view of accommodating even this latter class of work it will be seen in Figure 3 that the supporting column 10 is in the nature of 15 a sleeve slidably mounted upon a cylinder 23 arranged upon the base 11. The cylinder is interiorly screw threaded and a correspondingly screw threaded stem 24 is rotatably secured to the platform 14 and preferably has its upper end extending within the base of the same.

It will be obvious that a rotation of the stem 24 will result in a movement of the same with respect to a cylinder 23, this obviously resulting in a vertical movement on the part of the platform 14, and it will be seen, with a view of avoiding rotation of the supporting column 10 that I preferably secure a spring pressed pin 25 to the same, 30 the inner end of said pin riding in a longitudinally extending groove 26 formed in the inner face of the cylinder 23.

It will further be appreciated that a relatively complicated state of reduction gearing would be necessary to effect a rotation 35 of the stem 24 in view of the excessive weight of the platform 14 and elements carried thereby, and with a view of overcoming this difficulty it will be noted that the stem 24

40 has a gear 27 secured to its upper end, which gear is engaged by a corresponding gear 28 secured to a shaft 29, a worm wheel 30 being attached to the latter, and co-operating with a worm 31 so that the parts will at all times 45 be locked. The worm 31 is attached to a shaft 32 driven by gearing 33 associated with a shaft 34, and accordingly, in my present invention, I attach to the driving mechanism of the press a pair of gears 35 and 35' 50 providing clutch faces which are capable of being engaged by means of either face of a double clutch 36 keyed to the driving shaft, the latter being capable of being shifted by any suitable type of lever 37.

55 Further a supplemental shaft 38 is positioned adjacent the shaft upon which the clutch gear 36 is mounted, and this latter shaft mounts a pair of gears 39 and 39', and a gear 40, the latter being at all times engaged by the gear at the upper end of the shaft 34. Thus assuming that the driving shaft of the press is operating, it will be obvious that a shift of the clutch 36 to engage the gear 35' will result in an operation of 60 the corresponding gear 39' which will be

transmitted to the shaft 34 and thence by means of the gearing 33, worm 31 and shaft 29 to the stem 24, resulting in the operation aforescribed. A retraction of the parts to their normal position may be effected by 70 simply shifting the clutch 36 so that the movement of rotation of the shaft 34 will be reversed by virtue of the interposed gear 41, and obviously the entire platform will be lowered by this operation.

75 From the foregoing it will be seen that even the largest pieces of work, i. e., those which are capable of being accommodated by even removing the table 12 may readily be operated upon by simply effecting a lifting 80 of the entire platform driving mechanism, and drill head through the power drive provided for this purpose.

85 Thus all difficulty incident to work as incapable of accommodation, due to the height of the head, is avoided, leaving only the objection with respect to the distance existing between the head 13 and column 10; and with a view of overcoming this difficulty also, it will be noted that the platform 14 is provided in two sections 42 and 43, the former being preferably provided with a dove tailed portion 44 slidably accommodated in the correspondingly formed groove in the latter. The latter also mounts a screw 95 threaded shaft 45 which includes a screw threaded opening, forming a part of the portion 42, it being noted that a rotation of the shaft 45 is effected by means of a hand wheel 46.

100 Also the entire platform may be swung by retracting the spring pressed pin 25 so as to permit of a rotation of the sleeve comprising the pedestal.

105 By means of this construction it will be obvious that the two sections of the platform may be caused to move with respect to each other so that the head 13 may move in a horizontal plane, and thus accommodate varying widths of work beyond those capable of being disposed between the head and supporting column 10.

110 From the foregoing it will be seen that I have provided a certain construction by means of which a conventional size or even smaller size drill press or similar machine 115 is capable of operating upon various types of work of a size which it would have been incapable of heretofore accommodating. Thus due to the fact that the additional construction necessary for accomplishing this object is extremely simple, it will be seen that for only a minor cost a machine shop may have available a machine which will be capable of operating upon virtually any 120 size of work.

125 Obviously numerous modifications of structure might readily be resorted to without in the least departing from the spirit of my invention, which I claim as:

1. A drill press including a supporting column, comprising a sleeve, a base, an interiorly screw threaded cylinder secured to said base, a screw threaded stem mounted within said cylinder, a platform, said stem being carried by said platform, and means for rotating said stem. 30
2. A drill press including a supporting column, comprising a sleeve, a base, an interiorly screw threaded cylinder secured to said base, a screw threaded stem mounted within said cylinder, a platform, said stem being carried by said platform, an operating mechanism mounted upon said platform, and means for reversibly connecting said operating mechanism to said stem to effect a rotation of the latter in either a clock-wise or anti-clock wise direction. 35
3. A drill press including a supporting column, comprising a sleeve, a base, an interiorly screw threaded cylinder secured to said base, a screw threaded stem mounted within said cylinder, a platform, said stem being carried by said platform, an operating mechanism mounted upon said platform, a supplemental shaft, gears secured to said shaft, a clutch provided in said operating mechanism, means connecting said clutch with said shaft to effect a rotation thereof in either a clockwise or anti clock wise direction, a worm, a worm wheel engaged by 40 said worm, means for connecting said worm wheel to said stem, and means for connecting said worm to said supplemental shaft. 45

JULIUS EMMUEL CARLSON.
